UNITED STATES PATENT OFFICE.

OTTO HUBMANN, OF FRANKFORT-ON-THE-MAIN, GERMANY, ASSIGNOR TO AMERICAN LURGI CORPORATION, OF NEW YORK, N. Y., A CORPORATION OF NEW YORK.

PROCESS OF DISTILLING WET COMBUSTIBLE MATERIAL.

Application filed May 22, 1924. Serial No. 715,167.

To all whom it may concern:

Be it known that I, OTTO HUBMANN, a citizen of Germany, residing at Frankfort-on-the-Main, Germany, in the county of 5 Hesse-Nassau and State of Prussia, have invented certain new and useful Improvements in Processes of Distilling Wet Combustible Material, of which the following is a specification.

10 This invention relates to a process of distilling combustible materials containing considerable amounts of water, by means of combustible gases. It is well known that in processes of this character distillation is particularly promoted if the material to be distilled has been preliminarily well dried.

The distillation of wet combustible material by means of combustible gases is well known. It is also old to subject wet combustible material to a preliminary drying operation for which the heat is furnished by the combustion of gases. However, up to the present time nobody seems to have realized the possibility of a combination of 20 the two operations, as a unitary process in which the two operations favorably supplement each other, for the drying process and the distillation process differ materially in all essential characteristics. Whereas the 25 drying process involves a purely physical change taking place in the material at relatively low temperature, the distillation process involves principally chemical changes taking place at temperatures not lower than 30 400° C.

It has been found that an intimate interaction of the drying operation and the distilling operation may be so controlled that the two operations do not only not interfere with each other but actually supplement each other toward a common end.

For a full understanding of the invention, its principle of operation and its advantages, reference is had to the accompanying 45 drawing which is a more or less schematic representation of an apparatus by which the invention may be carried out.

In the drawing 1 represents a drying chamber disposed above and communicating 50 through a passage 21 at its bottom with the top of a still which provides for three sections in superposed relation. The uppermost section 2 is the distilling chamber proper, the gas or vapor space of which has an outlet 55 connected by means of a pipe 2* with an ex-

haust device 12, preferably of the ventilator type. The lower section 3 is provided as a regenerator space in which the sensible heat energy stored up in the coke or the residue of distillation in general may be 60 abstracted by a stream of gas passed through it, as will be more fully explained. Between the section 2 and the section 3 is provided a section 4 which serves the purpose to prevent a direct flow of gas from the section 3 65 into the section 2. Below the section 3 is a hopper portion 22 from which the material may be discharged from the still through a gate 22*.

The combustible gas is preferably produced by a generator 5 from which a pipe 10 leads to a gas admission chamber 11 which may form part of the still structure. The admission chamber communicates through two openings 11^a and 11^b with the 70 interior of the still. One of the openings (11^a) is on a level defining in substance the bottom of the distilling chamber 2 while the second opening (11^b) is on a level defining in substance the top of the regenerator space 75 3. In other words, the openings referred to lie substantially in two planes between which is disposed the space 4.

The air for the gas generator 5 is furnished by a blower 6 connected to it by a 80 pipe 7 containing a flow control device 7*. A pipe 9 may be provided for passing steam into the generator together with the air, as indicated.

The gaseous products of distillation, i. e., 85 the gases and vapors drawn from the vapor space of the distilling chamber 2 by the exhaust device 12, are passed through a tar separator 13, of any suitable construction and the so purified gases are then conducted 90 partly through a pipe 14 into the regenerator section 3 and partly through pipe 15 to the combustion chamber 17. Flow control devices 16 in lines 14 and 15 serve the purpose to vary at will the relative rates of 95 100 gas flow to the regenerator 3 and the combustion chamber 17, respectively.

A circulating system including a blower 18 or the like and pipes 18^a and 18^b leading into the bottom portion of the drying chamber 1 and out of the upper portion thereof respectively, passes the hot products of combustion from the combustion chamber 17 upwardly through the charge in the drying chamber. The combustion chamber 17 is 110

2
connected to the pipe 18^a leading from the blower 18 to the bottom portion of the drying chamber while a flue 19 connected to the pipe 18^b leading out of the upper portion 5 of the drying chamber carries into the atmosphere an excess of gas corresponding generally to the difference between the rate of gas flow into the drying chamber and the rate of flow out of it, which difference in 10 turn corresponds approximately to the rate at which the water is withdrawn from the charge.

From the blower 6 a pipe 8 leads directly to the combustion chamber 17 and by means 15 of a suitable control device 8^a the rate of flow of air through this pipe may be determined at will.

The mode of operation of the apparatus for carrying out the invention is as follows:

The drawing represents an apparatus in full working condition. The material in sections 3 and 4 of the still is the solid residue of distillation, i. e., coke or the like, 25 while the material in section 2 is undergoing distillation after previous treatment in the drying chamber 1. The charge in the drying chamber represents wet combustible material, for instance lignite, in a wet state 30 as it is found in various places.

The gas generator 5 is assumed to be in operation and the flow control devices are adjusted to determine the flow of air to the generator 5 and the combustion chamber 17. The control devices 16 in pipes 14 and 15 are adjusted to divide the gas coming 35 from the tar separator 13 in definite proportion, one part flowing to the regenerator section 3 and the other to the combustion chamber 17.

The gas flowing into the regenerator section 3 passes through the hot coke to the lower opening (11^b) communicating with the gas admission chamber 11 and mingling 45 with the gas coming from the generator 5 enters the distilling chamber 2 through the opening 11^a.

The three sections of the still terminate at their lower ends in contracted portions 50 which in conjunction with the wider upper portions of the adjoining sections define abrupt radial shoulders. The material passing downwardly through the still does not fill the peripheral corner spaces below the 55 shoulders so that peripheral gas spaces are formed at the upper end of sections 3 and 4 and at the upper end of the hopper 22.

The gas coming from the pipe 14 thus 60 may pass all around the gas space below section 3 and then rising uniformly through the column of coke in section 3 may be collected in the gas space below section 4 and then flow unimpeded to the lower opening 11^b. Similarly the gas passing from the 65 admission chamber 11 through opening 11^a

can freely pass through the gas space below the constricted portion of section 2 and then rise uniformly through the column of material undergoing distillation.

The column of coke in section 4 is of sufficient height to prevent direct flow of gas from section 3 upwardly into section 2.

It is apparent that the coupling of the drying operation with the distilling operation can be varied within wide limits. 70 Without first explaining the practical significance of such variations, it is obvious that by means of the valves 16 the gas coming from the separator 13 can be divided at will. Also the flow of air to the combustion chamber can be regulated at will by means of the valve 8^a. By varying the rate of gas generation, or in other words the volume and composition and also the temperature of the combustible gas and the rate of combustion and by varying, on the other hand, the gas flow through the regenerator section, the cooperation of the drying process and the distilling process may be adjusted 75 to the greatest advantage for the treatment 80 of materials whose water contents may vary within wide limits.

The practical significance may be understood from the following:

The drying process as applied to combustible material containing much water requires considerably more heat than the distilling process, in fact several times the amount necessary for the latter. This discrepancy in the expenditure of heat for the 90 two operations is, of course, generally taken care of in the invention by the fact that the distillation is carried out by means of the sensible heat energy of the hot generator gas, while the drying is done by the heat of combustion of the gases derived from the distillation, which include the generator gas. However, the general difference in the distribution of heat is in many cases not sufficient. In many instances the amount of 95 heat required for the distillation can not be furnished alone by the sensible heat of a volume of gas, the heat of combustion of which would be sufficient for the drying operation, especially since the temperature 100 of the distilling gas must not exceed a definite limit. In such cases the drying operation may be carried on farther than was heretofore the practice. In this manner it 105 is possible to almost perfectly balance the system. On the one hand a relatively greater amount of heat may be utilized for the drying operation, and, on the other hand, a relatively smaller amount of heat is made necessary for the distilling operation. To 110 more fully explain this phase, it may be mentioned that in the past wet lignite has been dehydrated to a point where the water content was about 15%-20%. Up to the 115 present it was held neither necessary nor 120

practical to carry the dehydration below the limit referred to. However, in the present invention where the sensible heat of the combustible gases and the heat of combustion of the gases coming from the still are correlated to a single unitary end, a carrying forward of the drying operation may be highly advantageous and desirable. In such cases an extension of the drying operation means a shortening of the distilling operation and a balancing of the system in such a way that according to the law of minima, a minimum amount of heat energy is expended for the process as a whole. It has been found that in extreme cases the dehydration of the material may be carried to a lower limit of 1-2%.

In fact, practical results have shown that the correlation of the drying operation and the distilling operation in the manner described not only leads often to an acceleration of the operation as a whole, but also brings about a considerable reduction and simplification of the apparatus. In addition to that, it should be noted that a decrease in the quantity of gas necessary for the distillation means a decrease in velocity of the gas out of the distilling zone, which in turn has a beneficial influence upon the dust content of the tar.

In fact, it has been found that in order to obtain distillation products which represent a maximum both as to quality and as to quantity, the water content of the dried material should not be above a certain limit. In certain kinds of lignite this limit was about 2% at which the recovery of tar was most favorable.

In the above remarks, the discussion of the coupling of the drying operation and the distilling operation has dealt with the flexibility of the system only in so far as the difference between the sensible heat energy of a combustible gas heated to temperatures suitable for distilling and the heat of combustion of the gas coming from the still permits a general working compromise between the two phases, i. e., drying and distilling.

In some cases it may not be possible in the manner just discussed to adjust the two phases to obtain the best results. A ready remedy is obtained by passing gas through the hot coke to abstract sensible heat energy therefrom and utilizing the heat thus recovered for the distillation.

It should be understood that the gas passed through the regenerating zone may be taken from any part of the system, either directly from the gas generator or from the tar separator as previously described.

By acceleration or by retardation of the flow of the gas through the regenerating zone it is possible to regulate the volume and the temperature of the distilling gas

within wide limits. By means of a system for circulating gas through the regenerating zone, it is possible to finely regulate the amounts of heat to be transferred to the drying chamber and the distilling chamber, respectively.

The heating of the combustible gas may be effected in the gas generator itself or in any other suitable manner. Instead of heating the gas by external means, it is, of course, possible to effect the heating by partial combustion, as will be readily understood. It is thereby immaterial whether the gas coming from the generator or the gas coming out of the regenerator zone or a mixture thereof is subjected to partial combustion.

The generator 5 has been referred to only in a general way, since there is considerable latitude in this direction. I prefer a gas generating plant including means for heating the gases produced, of a type that permits variation within wide limits of the volume, quality and temperature of the gas. The greater the adaptability of the plant in these respects, the greater is the flexibility of the system as a whole for the purpose of the invention.

In the foregoing special stress was laid upon the adaptability of the system to increase the transfer of heat to the distilling chamber. If it is found necessary or desirable to at any time effect a relative increase in the transfer of heat into the drying chamber, it is only necessary to restrict the flow of gas to the regenerating section 2 to cause a proportionately larger flow of the gas to the combustion chamber 17.

In case no separate source of power is available for doing the work involved in driving the blowers of the system, the gas of the gas generator or of the system in general, may, of course, be used, in which case special provision is made therefor.

I claim:

1. In a process of distilling wet material which is decomposable by heat to form a combustible gas and a solid residue, involving the drying of said material to any certain degree and the distillation of the dried material, the steps which consist in moving said material to be treated successively through a drying zone and a distilling zone, maintaining a flow of combustible gas heated to distilling temperature through the material in the distilling zone, burning at least part of the gaseous products evolved from said material, passing the resulting products of combustion through the material in the drying zone, and regulating the volume, temperature and composition of said combustible gas and the burning of said evolved gaseous products to effect the drying of the material in the drying zone to said certain degree.

2. In a process of distilling wet material which is decomposable by heat to form a combustible gas and a solid residue, involving the drying of said material to any certain degree and the distillation of the dried material, the steps which consist in moving the said material to be treated successively through a drying zone, a distilling zone and a cooling zone, maintaining a flow of a combustible gas heated to distilling temperature through the material in the distilling zone, passing a gas through the hot solid residue of the distillation in the cooling zone and then through said material in said distilling zone, burning at least part of the gaseous products evolved from said material in the distilling zone and passing the resulting products of combustion through the material in the drying zone, and regulating the volume, temperature and composition of said combustible gas passed through the material in the drying zone, the volume of said gas passed through the hot solid residue of the distillation in the cooling zone and the burning of the said evolved gaseous products to effect the drying of the material in the drying zone to said certain degree. 25
3. Process as defined in claim 2 in which said gas passed through the hot solid distillation residue is a gas from the system. 30
4. Process as defined in claim 2 in which said gas passed through the hot solid distillation residue is a part of the gaseous products of the distillation. 35
5. Claim according to claim 1, in which part of the resulting gaseous products of distillation is returned and admixed to the combustible gas entering the distilling zone. 40
6. Claim according to claim 1, in which part of the resulting gaseous products of distillation is heated, and then returned and admixed to the combustible gas entering the distilling zone.

In testimony whereof I affix my signature.
OTTO HUBMANN.
